UNITED STATES PATENT OFFICE.

CORNELIUS H. VANDONK, OF WELLS, MICHIGAN.

FREIGHT-CAR STAKE-POCKET.

1,156,566.

Specification of Letters Patent. Patented Oct. 12, 1915.

Application filed January 15, 1915. Serial No. 2,311.

To all whom it may concern:

Be it known that I, CORNELIUS H. VANDONK, a citizen of the United States, residing in the city of Wells, county of Delta, 5 and State of Michigan, have invented certain new and useful Improvements in Freight-Car Stake-Pockets, of which the following is a specification.

My invention relates to improvements in 10 freight car stake pockets, and particularly refers to a construction of pocket which is organized in such a manner as to release the stake when desired.

In the accompanying drawings, which 15 form a part of this specification Figure 1 is a front elevation of my improved pocket; Fig. 2 is a side elevation of Fig. 1; Fig. 3 is a plan view of Fig. 1, shown partly in section, the section being taken along the 20 line 3—3 of Fig. 1; Fig. 4 is a back elevation of the pocket, the upper portion being broken away to conserve space; Fig. 5 is a section taken on the line 5—5 of Fig. 4; Fig. 6 is a front elevation of the lower portion 25 of the pocket, showing the swinging gates opened up to release the stake; Fig. 7 is a sectional plan view taken on the line 7—7 of Fig. 4; Fig. 8 is a perspective view of the worm element; Fig. 9 is a side elevation 30 of a portion of a freight car sill or frame, showing the application of my improved pockets; and Fig. 10 is an end elevation of the locking mechanism associated with the common actuating member for the 35 pockets on the sill, shown in Fig. 9.

In my previous Patents, No. 1,024,608, April 30, 1912, and No. 1,074,668, October 7, 1913, I have shown and described two types of pockets which are concerted with 40 movable elements adapted to release the car stakes when desired. However, although these devices are eminently practical and efficient, my construction described herein will be found to possess certain valuable 45 features and advantages not present in the patented pockets referred to.

The construction shown and described herein contemplates the provision of a pocket of the class referred to, which shall be exceptionally simple, substantial and rugged in construction; one in which the operating parts are comparatively few in number and capable of being manufactured 50 very economically from relatively cheap 55 materials, and in which each part may be so designed as to possess exceptional in-

herent strength, consistent with the function which it has to perform, and one in which the general arrangement of the pocket is such as to provide a very neat, compact, 60 practical and efficient construction.

In the specific embodiment which I have selected as an illustration to demonstrate the application of my invention, 20 represents the sill or side frame of a freight car, to the 65 side of which are applied my improved pockets, each designated as a whole 21. These pockets are released or closed by means of a common actuating member which in this case takes the form of a rod 70 22, square in section, which extends substantially the entire length of the sill and beneath the openings of the pockets for the stakes 23. The pocket, as its principal part, comprises an integral cast-iron member 24, 75 the general shape of which is shown in Figs. 1 and 3. The cross-section of this main integral casting 24 is such as to give the desired strength and stiffness, and in the front of said casting 24 there is provided a substantially rectangular opening 25, the back 80 and bottom of which are shaped to correspond with the lower end of the car stake, the front of the opening, however, being left open so as to permit the stake to be released when necessary. When the stake is in use, the front of the pocket must be closed so as to prevent the stake from dropping out, and this is effected by means of a pair of vertically swinging doors or gate members 26 which are pivoted upon a pair of vertical pins 27 and substantially meet at 85 the center of the front of the pocket opening, and thus completely inclose the lower end of the stake. The hinge connections between the main pocket casting 24 and the swinging gate members 26 are effected by virtue of a series of lugs 28 and 29 on the main casting, which are drilled out to correspond with similarly drilled lugs 30 on the gate members 27 and interposed between the hinge lugs of the main member 24. The 90 general shape of the gate member is somewhat similar in section to an angle-iron, as shown in Fig. 3, this section being strengthened by means of a plurality of integral ribs 31 formed as continuations of the hinge lugs 30. It should be noted that the bottom wall of the pocket opening is partly formed by 95 an integral sloping portion 32 in the main pocket casting 24, and is partly formed by a pair of inwardly projecting horizontal webs 100 105 110

33 forming parts of the gate members 26. Adjacent the meeting line of these horizontal web parts 33, the latter are beveled off, as shown at 34, so as to permit the stake to drop out when the gate members 26 are swung outwardly on their pivots to effect its release, this being clearly shown in dotted lines in Fig. 3. The main body casting 24 is suitably drilled out at 35 so as to accommodate fastening bolts to secure it to the sill of the car.

Describing now the operating mechanism for swinging the gate members 26 vertically on their pivots into open or closed position and for locking them against improper movement, it will be seen that the bottom of the main pocket casting 24, beneath the pocket opening, carries a pair of integral depending lugs 36, suitably conformed with ribs 37 and 38 so as to furnish the desired strength and rigidity, and bored out transversely, *i. e.*, horizontally and longitudinally of the car, so as to accommodate a rotary worm element or cam 39, shown in perspective in Fig. 8. This worm element is a single casting, the body of which 40 is cylindrical in shape, and on the exterior of which cylinder are formed a set of integral cams or worms 41 and 42, 42. The ends of the cylinder 40 extend some distance beyond the outer faces 43 of the similarly shaped cams 42, 42 and constitute journals which are adapted to rotate in the holes bored out transversely in the depending lugs 36. It should be noted that the overall length of the worm element is somewhat less than the space between the inner edges of the ribs 38, in addition to which the upper portions of the lugs 36 are cut away, as shown in full lines in Fig. 4 and in dotted lines in Fig. 2, so as to permit the worm element to be removed bodily from its bearings in the pocket casting 24 when occasion arises to assemble or repair the device.

45 Describing the coöperation between the cam element 39 and the gate members 26, it will be observed that the lower ends of the gate members on the under side of the webs 33 are provided with integral depending cams 44. As shown in Fig. 7, the inner adjacent faces 45 of said cams 44 are adapted to co-act with the outer faces 46 of the central pointed cam 41, hereinafter called the closing cam, and their outer faces 47 co-act with the inner faces 48 of the outer cams 42, hereinafter called the opening cams. Assuming that the pocket is in closed position, as shown in Figs. 4 and 7, it is apparent that a rotary movement of the worm element in the direction of the arrow 49 will cause the outer points of the cams 42, 42 to enter between the inner surfaces of the lugs 36 and the outer cam surfaces 47 of the cams 44, and will cause a rotary movement of the gate members 26 upon their pivots 27. The pro-

jected position of said pivots 27 is indicated at points 27^a in Fig. 7, although they are cut off. The extent of the rotary movement of the member 39 and the shape of the opening cams are such as to open the gate members into the position shown in dotted lines in Fig. 3, with the rear ends 50 of the webs 33 substantially in engagement with each other, and thus, if desired, forming a stop to arrest further unnecessary movement. In order to swing the gate members back into closed position, the worm element 39 is rotated in the reverse direction from that shown by the arrow 49, and the point of the cam 41 is thus caused to enter between the inner cam faces 45 of the cams 44, which are then substantially in contact with each other; and as said member 39 commences to rotate, the wedge-shaped cam surfaces 46 of the said cam 41 will co-act with the cam surfaces 45 of the cams 44 and force the latter apart, thus effecting a rotation of the gate members 26 upon their pivots until they attain their normal position, shown in Figs. 1, 2, 3, 4, 5 and 7. The rotation of the worm element is, however, continued beyond the time after which the cam surfaces 46 and 45 become ineffective to rotate the gate members further, this further rotation being permitted by reason of the parallel character of the extensions 51 of the pointed cam surfaces 46; this further rotary movement of the worm element bringing the outwardly extended parallel portion 52 between the now parallel inner edges 53 of the webs 33 on the lower ends 100 of the gate members. In order to arrest the movement of the worm element after it has been rotated into the above described self-locked position, I form at the front edge of the parallel portion 52 an outwardly extending lip 52^a which strikes against the under side of the webs 33, and thus arrests the rotation of the worm element. This outwardly projecting parallel portion 52, just referred to, is extended radially from the axis of the worm element a sufficient distance to bring a substantial portion of said parallel portion 52 between said two parallel surfaces 53. In this connection, it should be noted that the pivots 27 are located a substantial distance 115 outward from a vertical plane in which is located the axis of the worm element 39; thus, after the worm element has closed the gates, and after it has continued its rotation into the locking position, as shown in Figs. 120 2 and 5, it will be found to be impossible to effect movement of the worm element by attempting to swing the gate members outwardly away from the pocket. Thus, it is manifest that I have provided a cam or worm 125 connection between the gate members and the rotary element 39 of such character that the movement is irreversible with respect to the closing movement, and this construction is self-locking, which is of great advantage 130 135 140 145 150 155 160 165 170 175 180

in devices of this general type. It is also apparent that the operating parts are so organized as to be located entirely below the bottom of the pocket opening and thus are so situated as to be entirely free from abuse or harsh treatment.

Describing the means for rotating the worm elements 39 it will be observed that these elements are cored out axially with a square hole 54 extending longitudinally the entire length of the cylindrical portion 40, and through which passes the square actuating shaft 22, previously referred to. The extreme end of this shaft 22 preferably extends slightly beyond the end of the sill 20 so as to permit the convenient application of a suitable wrench so as to turn the shaft the proper amount necessary to effect the desired pivotal movement of the gate members 26. Adjacent the end of the sill, this shaft 22 is supported in a bearing member 55, which, in this instance, takes the form of a flanged bushing cored out axially with a square hole to admit the shaft 22, and having at its outer end a pair of flat lugs 56 extending along two opposite sides of the shaft 22, which latter is prevented from moving axially with reference to the bushing by virtue of a split cotter 57 which passes through said lugs 56 and through a hole drilled transversely through the shaft 22. This flanged bushing 55 is rotatably supported in a hanger 58, this being constructed with a removable cap 59 bolted thereon so as to permit insertion or removal of said flanged bushing 55. The hanger 58 is suitably ribbed to provide the maximum strength and rigidity and is secured to the sill 20 of the car by means of a pair of bolts 60.

Describing the subsidiary locking device for preventing vibration of the car from causing the gradual rotation of the rod 22 and of the worm elements and thus causing improper opening of the pockets, I show in Figs. 9 and 10 a pawl member 61 which is rigidly secured to the end of the shaft 62, journaled in the hanger bracket 58 parallel with the shaft 22, the other end of said shaft carrying a handle-piece 63 which permits the pawl 61 to be readily raised out of locking engagement with the flanged bushing 55. The locking of said flanged bushing 55 is actually effected by virtue of the depending arm 61 engaging a cam portion 64, which is formed as a projection or extension of the edge of one of the flanges of the bushing 55. The position of said cam projection 64 is such that the locking arm 61 is adapted to fall behind and engage the front abrupt face of said cam 64 when the shaft 22 is turned until the pockets are completely closed and the shaft has completed its continued rotary movement and placed the closing cams in self-locked position. In order

to free the shaft 22 so as to permit it to be rotated to open the pockets, that is to say, in the direction of the arrow 65, the operator manipulates the hand-lever 63 and throws the locking arm 61 backwardly until the lower edge thereof passes rearwardly beyond the point of the cam 64. This obviously permits the shaft to be rotated and the pockets to be opened to release the stakes. In order to prevent the operator from improperly throwing back the locking arm 62 too far, I provide a pin 66 fixed in the side of the hanger 58 which engages the rear edge of said locking arm 62 and prevents excessive movement thereof. Owing to the carelessness of the relatively unskilled help employed in handling freight cars, and particularly flat cars of this type, which are ordinarily employed in the shipment of logs, I have found that it is advisable to make the operation of closing and locking the pockets as automatic as possible. Hence, in order to prevent a careless employee from leaving the parts unlocked, that is, with the locking arm 61 in its unlocked position 90 against the pin 66, I form on the opposite side of said locking arm a small projecting cam or dog 67 which swings down into the path of the point of the cam 64 when said arm 61 is moved into engagement with the pin 66. Thus when the shaft 22 is turned in the direction of the arrow to open the pockets, the point of the cam 64 strikes the point of the dog 67 and throws the locking arm 67 back approximately into its normal locked position, 95 with its lower edge in engagement with the rear face of the cam 64. It is manifest that when the rod 22 is turned to close the pockets, the lower edge of the locking arm 61 will drag over the rear face of the cam 64 until the point of the latter slips past said lower edge on the completion of the closing movement of the rod 22, and the arm 61 will then fall by gravity behind the front locking face of the cam 64, and the entire 100 mechanism will thus be automatically placed in locked position.

It should be understood that the construction described is capable of being modified in many of its details without departing 115 from the spirit of the invention, hence I do not wish to be limited, except as specified in the appended claims.

I claim—

1. The combination of a car stake pocket 120 provided with a gate member adapted to swing on a substantially vertical pivot, a horizontal shaft, and an interengaging member carried respectively by said gate member and said shaft, and adapted positively to 125 effect both opening and closing pivotal movements of said gate upon rotation of said shaft.

2. The combination of a car stake pocket 130 provided with a gate member adapted to

swing on a substantially vertical pivot and form a closure for said pocket, adapted, upon its rotary movement, to open said closure and release the stake, a shaft, and cams respectively carried by said gate member and said shaft, coöperating to effect rotation of said gate member upon rotation of said shaft.

3. The combination of a car stake pocket 10 provided with a gate member adapted to swing on a substantially vertical pivot, a horizontal shaft journaled in the lower end of said pocket beneath the bottom wall of the pocket opening, and interengaging cams 15 carried respectively by said shaft and by the lower end of said gate member and adapted to effect rotation of said gate member to open said pocket upon rotation of said shaft.

4. The combination of a car stake pocket 20 provided with a pair of opposed gate members mounted on vertical pivots on either side of the pocket opening and adapted to swing outwardly away from each other to release the stake, and common actuating 25 means for rotating said gate members in either directions.

5. The combination of a car stake pocket provided with a pair of opposed gate members mounted on vertical pivots at the sides 30 of the pocket opening and adapted to swing outwardly to release the stake, a horizontal shaft having its axis a substantial distance beneath the bottom of the pocket opening, cams carried by the lower ends of said gate members beneath the bottom wall of said pocket, and a common cam element carried by said shaft and adapted to coöperate with the gate cams to effect rotation of said gate members.

40 6. The combination of a car stake pocket provided with a gate member adapted to swing on a substantially vertical pivot, a horizontal shaft journaled in the lower end of said pocket and having its axis beneath 45 the lower end of said pocket opening and closer to the sill of the car than the pivotal axis of said gate member, and a cam carried by said shaft and having operative engagement with the lower end of said gate member, said cam being provided with a surface 50 adapted to effect a rotary closing movement of said gate member, and being provided with a second engaging surface adapted to

form a lock for said gate member after its closing movement has been effected. 55

7. The combination of a car stake pocket provided with a pair of opposed gate members mounted on vertical shafts at the sides of the pocket opening and adapted to swing outwardly to release the stake, a horizontal 60 shaft having its axis beneath the pocket opening and closer to the sill of the car than the pivotal axes of said gate members, cams carried by the lower ends of said gate members, and a cam carried by said shaft having a 65 pair of similar cam surfaces arranged in wedge relation and adapted simultaneously to engage the cams on the lower ends of said gate members and effect a closing movement of the latter, and provided with a pair of parallel surfaces adapted to engage the lower ends of said gate members upon continued rotary movement of said cam, and after said gate members have been brought into closed position. 70

8. The combination of a car stake pocket provided with a pivoted gate member adapted normally to prevent displacement of the stake, and means for forcibly opening and closing said gate member. 80

9. The combination of a car stake pocket provided with a pair of opposed gate members mounted on vertical pivots on either side of the pocket opening and adapted to swing outwardly away from each other to 85 release the stake, a horizontal shaft and mutually coöoperating interengaging members carried respectively by said shaft and gate members, adapted positively to effect both opening and closing rotary movements 90 of said gate members.

10. The combination of a car stake pocket provided with a pivoted gate member adapted normally to close the pocket opening and capable of being swung on its pivot to release the stake, a shaft, and interengaging cam members carried respectively by said shaft and said gate members coöperating together to effect positive opening and closing movements of said gate member by the 100 actuation of said shaft. 95
